UNITED STATES PATENT OFFICE.

EDWIN W. DUNCAN, OF WOODWARD, ALABAMA.

MUD GUN.

Application filed May 25, 1925. Serial No. 32,861.

To all whom it may concern:

Be it known that I, EDWIN W. DUNCAN, a citizen of the United States of America, residing at Woodward, in the county of Jefferson and State of Alabama, have invented certain new and useful Improvements in Mud Guns, of which the following is a specification.

My invention relates to mud guns for stopping the tapping holes or iron notches of blast furnaces and the like.

Mud guns of the character in question, as heretofore constructed, have comprised a barrel having therein a close fitting plunger reciprocated by an air or steam cylinder and adapted to be retracted beyond a filling opening for the mud in order that the latter might be charged ahead of the plunger and be rammed thereby into the furnace tapping hole to stop it. This obviously will leave the filling opening in the barrel in free communication with the interior of the furnace for a part of the time during each charging operation, which is objectionable for many operating reasons, chief of which is the necessity of materially cutting down or shutting off the blast in the furnace to avoid blowing out through the mud gun.

The object of my present invention is to design a mud gun in which the plunger will at all times positively cut off communication between the filling opening of the gun or the atmosphere and the interior of the furnace. This is accomplished by providing the barrel, opposite the filling opening with any desired number of longitudinal grooves through which the plunger, as it is drawn outwardly, will force the charge of mud introduced behind it to by-pass the plunger and assume position ahead of it so that on the operating stroke of the plunger the mud will be rammed into the forward end of the gun or into the tapping hole in the usual manner. In all positions the plunger thus positively prevents any danger of the furnace blowing out through the mud gun barrel and makes it generally unnecessary to reduce the blast pressure.

My invention further comprises the novel details of construction and arrangements of parts, which in their preferred embodiment only are illustrated in the accompanying drawings which form a part of this specification, and in which:

Fig. 1 is a longitudinal cross-sectional view through a complete mud gun.

Fig. 2 is an enlarged fragmental cross-sectional view through the grooved portion of the gun barrel taken on the line 2-2 of Fig. 3; and

Fig. 3 is a transverse cross-sectional view taken on the line 3-3 of Fig. 2.

Similar reference numerals refer to similar parts throughout the drawings.

In the embodiment of my invention illustrated, I show a mud gun having a barrel 1, with a nozzle 2 adapted to enter the tapping hole of the furnace and having its outer end closed by a head 3 having a hole 4 through which the operating rod 5 for the plunger 6 of the gun passes. The rod is operated by a piston 7 moving in a cylinder 8 and operated by any suitable fluid pressure in accordance with well understood practice.

The gun is provided near its outer end and in the upper portion thereof with a filling opening 9 through which the mud is charged into the barrel behind the plunger. The lower half section of the outer end of the barrel is enlarged and cast with a series of longitudinal grooves 10 which at one end merge gradually into the forward cylindrical end of the barrel and at the other end 11 they slope up towards the gun barrel head 3 and have communication with a countersunk recess 12 therein. It will be observed that the plunger stands normally in the forward end of the barrel and acts to plug or close same so as to intercept positively communication between the tapping hole of the furnace and the charging opening in the mud gun barrel. The barrel head has in its upper portion a downwardly inclined port 13 drilled and tapped therethrough and normally closed by a plug. By removing the plug this hole is adapted to receive a pipe for delivering a cleaning spray of water into the mud gun barrel to clean it out.

The mud is introduced with the plunger in this forward position and upon retraction of the plunger the mud is forced against the head 3 and caused to pass through the by-pass grooves and assume position in the barrel head of the plunger. It will be noted that the plunger, before exerting pressure on the mud will have moved into position to seal or close the opening 9 on all sides and that in this way it forces the mud, when compressed between it and the head 3, to escape only through the by-pass grooves which are just long enough for the

mud to pass therethrough into position ahead of the plunger. When the plunger is thrust forward the mud will be driven into the tapping hole in the manner well understood. It will be seen that at all times the plunger forms a plug or valve which intercepts communication between the tapping hole and the charging hole 9 of the gun.

Though I have described with great particularity the details of the embodiment of the invention herein shown, it is not to be construed that I am limited thereto, as changes in arrangement and substitution of equivalents may be made by those skilled in the art without departing from the invention as defined in the appended claims.

Having thus described my invention, what I claim as new and desire to secure by Letters Patent, is:—

- 20 1. In a mud gun having at an intermediate point in its barrel a charging opening for mud, a reciprocable plunger adapted to seal said charging opening, and a by-pass opening on opposite sides of said charging opening through which mud responsive to a movement of the plunger away from the discharge end of the gun is adapted to be moved into position in front of the plunger, as and for the purposes described.
- 25 2. In a mud gun having at an intermediate point in its barrel a charging opening for mud and having its barrel opposite said

opening enlarged and provided with longitudinal by-passes, and a reciprocable plunger of less length than said by-passes 35 but wide enough to seal said charging opening and which is adapted in all positions to prevent free communication between the discharge end of the gun and its charging opening.

3. A mud gun of the character described comprising a barrel having a cylindrical bore in its discharge end and having its intake end enlarged and provided overhead with a charging opening and below with a plurality of longitudinal by-pass grooves leading from the outer end of the barrel to an intermediate point in the barrel beyond the charging opening, and a plunger less in length than the by-pass grooves and adapted 45 at all times to prevent free communication between the discharge end of the gun and its charging opening.

4. A mud gun in accordance with claim 3, in which the grooves are arranged 55 throughout the lower half circle of the barrel and at their outer ends slope upwardly and merge into a mud receiving chamber provided between the charging opening and a head closing the outer end of the barrel. 60

In testimony whereof I affix my signature.

EDWIN W. DUNCAN.
